US00D976496S

(12) **United States Design Patent** (10) **Patent No.:** **US D976,496 S**
Liu (45) **Date of Patent:** **** Jan. 24, 2023**

(54) **ARCH PAD**

(71) Applicant: **Shenzhen Dingji Technology Co., Ltd.**, Shenzhen (CN)

(72) Inventor: **Chengfei Liu**, Yongxing (CN)

(**) Term: **15 Years**

(21) Appl. No.: **29/865,648**

(22) Filed: **Aug. 5, 2022**

(51) LOC (14) Cl. **24-02**

(52) U.S. Cl.

USPC **D29/121.2**

(58) **Field of Classification Search**

USPC **D29/121.2; D24/192**
